UNITED STATES PATENT OFFICE.

HERMAN C. COPENHAGEN, OF AUBURN, WASHINGTON.

DIRT-WAGON.

1,153,179.

Specification of Letters Patent.

Patented Sept. 7, 1915.

Application filed January 16, 1914. Serial No. 812,387.

To all whom it may concern:

Be it known that I, HERMAN C. COPENHAGEN, a citizen of the United States, residing at Auburn, in the county of King and 5 State of Washington, have invented certain new and useful Improvements in Dirt-Wagons, of which the following is a specification.

This invention relates to wheeled vehicles, 10 and has particular reference to that class known as dump-wagons having drop-doors at the bottom of the wagon box.

The object of the invention is the provision of mechanism under the control of a 15 driver whereby the rear end of a wagon body may be lowered into convenient position to be loaded, and the provision of devices for restoring the body to its normal raised position by means of mechanism 20 which is operated through the agency of one of the wagon-wheels during the forward travel of the same.

A further object is to provide releasable means for positively supporting the wagon- 25 body when in its elevated position.

The invention is illustrated in the accompanying drawings, in which—

Figure 1 is a side elevation of a dump-wagon with my invention applied thereto, 30 and with one of the rear wheels omitted and the axle thereof in section. Fig. 2 is a longitudinal vertical section of the same but with the body shown in its lowered position and the drop-doors closed. Fig. 3 is a plan view. 35 Fig. 4 is a rear elevation of the wagon with the various parts thereof disposed as shown in Fig. 2. Fig. 5 is a detail perspective view of the stirrup hanger for the rear end of the wagon-box.

40 The wagon-body or box 10, as shown, is of the hopper type and is provided at the bottom with gravity-openable doors 11 which are connected to the side walls of the box by hinges 12.

45 The free ends of the doors are each supported by a chain 13 secured at one end to the box to the rear of the door and passing below the latter and in front of the box through a guide 14 and pulleys 15 to a winding drum 16 which is journaled in bracket- 50 supports 17 secured to the box.

55 Provided on the drum-axle is a ratchet-wheel 18 for engagement by a pawl 19 carried by a lever 20 fulcrumed on the drum axle and extending to within convenient reach of the driver's seat 21. A dog pro-

vided on a treadle 22 is utilized to secure the drum against the accidental unwinding of the chain therefrom except when the wagon-load is to be dumped when the treadle is pressed downwardly to release the drum, whereupon the weight of the load upon the doors 11 will cause the same to drop with a consequent discharge of the load. The aforescribed parts may be of 60 ordinary or suitable construction except that the referred to parts are connected to the wagon-body to be carried therewith when the same is swung up or down.

According to my improvements the wagon 70 frame is constituted of two longitudinally arranged girder members 23 and 23¹ disposed at opposite sides of the body 10 and transverse members 24 which are secured to said longitudinal members to furnish a rigid 75 framework. The forward end of such framework is borne upon suitable supports which are carried by the "fifth wheel" 25, while at the rear end the framework is supported upon the bearing boxes 26 for a rotary transverse shaft 27 which constitutes the axle for the supporting wheels 28 and 28¹ which are rotatable independently upon journals provided at the ends of the axle. One of the wheels, as 28, is, however, adapted 80 to be coupled to the axle through the medium of crown clutch element 29 which is splined to the shaft, coöperating with a clutch element 30 formed on or rigidly secured to the hub of said wheel. The clutch element 29 is actuated by means of a forked bell-crank lever 31 having studs engaging within a peripheral groove provided in the clutch element 29 and actuated through the agency of a pull-rod 32 connected with an operating lever 33 fulcrumed to the frame-member 23 adjacent to the driver's seat. 85

90 Boxes 10¹ and 23² are respectively secured to the front of box 10 and frame members 23 and 23¹ for a transverse rod 10² to afford 95 hinge connections between the box and the frame.

100 Boxes 34 secured to the frame members 23 and 23¹ afford bearings for a transverse shaft 35 which is located above the axle 27. Box-hoisting lines 36 are secured at one end 105 to the respective frame members 23, 23¹, thence pass about sheaves 37 connected to the lower end of the box 10, whence they pass over pulleys 38 provided on the shaft 35 and have their other ends secured to the 110 axle 27. To elevate the rear end of the box,

the wheel 28 is clutched to the axle as the wagon is traveling forward, resulting in the axle being rotated with the wheel to wind up the lines with a consequent hoisting of 5 the rear end of the box. When the box is thus raised, it is supported by means of a U-shaped bar or hanger 39, Fig. 5. More particularly, said hanger comprises a horizontally disposed box-supporting part 40 having at each end an upwardly extending arm 41 which is bent to afford bearing portions 42 which are journaled in bearings provided in the frame members 23 and 23¹.

Extending rectangularly, or nearly so, 15 from one of the arm portions 42 is an arm 43 which is connected by a reach rod 44 with a lever 45 connected by a pivotal pin 45¹ to the front end of the wagon frame.

46 represents a wheel keyed or otherwise 20 rigidly secured to the axle 27 and 47 is a brake-strap passing about the underside of the wheel 46 and having its ends secured to studs 48 projecting from the frame member 23¹. The brake-strap lead 47¹ which is 25 forward of the axle and wheel is disposed to be encountered by the hanger-part 40 when the same is swung rearwardly in withdrawing it from beneath the wagon-box; then, by the further rearward movement of 30 the hanger-part the brake-strap part 47¹ is bent out of a straight line to shorten the effective length of the strap and thereby cause the latter to embrace the wheel 46 with a braking action. By such devices the operator 35 manipulates the lever 45 to throw the hanger-part 40 rapidly from the position in which it is illustrated in Fig. 1 into engagement with the strap (see Fig. 2) so that the descending movement of the rear end of the 40 wagon box may be checked; then, by slightly relieving the pressure of the hanger against the strap, the box may be gradually lowered. When it is desired to elevate the wagon-box, 45 the lever 45 would be regulated to swing the hanger into neutral position; that is to say—clear of the brake-strap and not sufficiently far to interfere with the box, whereupon the box may be raised as before explained, and then the hanger-part 40 would 50 be swung beneath the body to receive it when the clutch devices are disengaged.

Provided at each side of the box is a chain 49 having its ends connected with the box and the frame-members 23 and 23¹ to supply means to limit the downward swing of the box and to relieve the lines 36 of strains 55 when the box is being loaded. A spring 32¹ provided on the rod 32 and acting between a stop 50 which is rigid with frame-member 60 23 and a collar 51 provided on the rod, tends to push the rod rearwardly and yieldingly

hold the clutch element 29 out of engagement with its mate 30.

The operation of the invention will, it is thought, be understood from the foregoing 65 description.

Among the advantages of the invention is, first, that by lowering the wagon-box for loading, the labor of shoveling dirt or other material is lessened by reason of the workmen having to raise the dirt or other material but a relatively short height; second, the wagon box is raised gradually during the forward travel of the wagon, say in a distance of ninety feet, whereby the increased work upon the draft animals is thereby rendered of little moment; and, third, the wagon box when raised, is sufficiently high to allow the doors thereof to drop unobstructedly when the load is being dumped.

What I claim, is—

1. In a wagon, the combination with the wagon-frame, a box hingedly connected at its forward end to said frame, supporting 85 wheels for the frame, the axle for the rear wheels being rotatably connected to said frame, a hoisting line connected with the rear end of said box and attached to said axle, and means for releasably coupling said axle to one of said wheels whereby the turning of the latter in the forward travel of the wagon will cause the line to be wound about the axle to elevate the box, of means for regulating the lowering of the box when the same is to be loaded, and means connected with said frame for suspending the box in its lowermost position.

2. In a wagon provided with a frame and a box hinged at its front end to said frame means for raising and lowering the rear end of said wagon-box, brake devices for controlling the speed of the box when lowered, means for supporting the wagon-box in its elevated position, said means also serving to actuate said brake devices.

3. In a wagon provided with a frame and a box hingedly connected at its front end to the frame, means to raise and lower the rear end of said box, means connected with the frame for suspending the box in its lowermost position, and a hanger connected to said frame and engageable with the underside of the box for supporting the latter when in its elevated position.

Signed at Seattle, Wash., this 9th day of January, 1914.

HERMAN C. COPENHAGEN.
